UNITED STATES PATENT OFFICE.

PERRY FLORA, OF OWINGSVILLE, KENTUCKY.

BIT-STOCK.

1,003,098.

Specification of Letters Patent. Patented Sept. 12, 1911.

Application filed January 28, 1910. Serial No. 540,678.

To all whom it may concern:

Be it known that I, PERRY FLORA, citizen of the United States, residing at Owingsville, in the county of Bath and 5 State of Kentucky, have invented certain new and useful Improvements in Bit-Stocks, of which the following is a specification.

My invention relates to that form of 10 wrench or brace in which a ratchet is used, operable in either direction, and having a handle carrying pawls engaging with the ratchet when the handle is operated in either direction, means being also provided 15 for engaging both of the pawls with the ratchet so that the ratchet and handle will operate together in both directions.

The object of the invention is to provide 20 a very simple and convenient tool of this character having a handle projecting out at right angles to the body of the brace or wrench, whereby increased leverage may be secured, and also provided with a pressure knob which may or may not be used, as de- 25 sired, this knob entering the shank of the implement immediately behind the tool held therein, but being detachable therefrom, if wished.

For a full understanding of the invention 30 and the merits thereof, and to acquire a knowledge of the details of construction, reference is to be had to the following description and accompanying drawings, in which:

35 Figure 1 is a side elevation of one form of my improved wrench; Fig. 2 is a section thereof on the line 2—2 of Fig. 4; Fig. 3 is a side elevation, partly broken away, of another form of my wrench; Fig. 4 is a 40 fragmentary section on the line 4—4 of Fig. 2. Fig. 5 is a transverse section on the line 5—5 of Fig. 4.

Corresponding and like parts are referred 45 to in the following description and indicated in all the views of the drawings by the same reference characters.

My improved implement, in the form shown in Fig. 1, consists of a hollow body 2, shown in detail in Fig. 2, open at its rear 50 end and extending laterally at 2^a, this body constituting a sleeve which surrounds a shaft 5, as will be later described. The

rear open end of the body is closed by a covering plate 3 which extends along the angular extension 2^a, as shown, and held in 55 place by screws 4 located at one end, and by screws 4^a at the other. Carried within the body or sleeve 2 is the shaft 5 having at its rear end the ratchet 6 and at its forward end where it projects beyond the sleeve 2, 60 the tool-engaging head 7 having therein the socket 8 for the reception of a tool, said head entering into an annular recess formed in the end of the body so as to give a very rigid bearing for the head and for the 65 shaft. Mounted within the angular extension of the sleeve 2 are the opposed pawls 9. There are two of these pawls opposite to each other and engaging on opposite sides of the ratchet, said pawls being cut away 70 so that while the bases of the pawls bear against each other, the tooth of each pawl is as wide as the ratchet 6, thus securing a firm engagement of the pawls with the ratchet. A screw 10 passes through the 75 covering plate 3 and through the pawls to form a pivot pin for the same, the covering plate being countersunk to receive the head of the pin. In order that either pawl may move out of engagement with the ratchet 80 teeth, each pawl has a laterally projecting lug 11 extending into the opposed slots 12 formed in the wall of the angular extension, the lugs being long enough to project through the wall when the pawls are in 85 engagement with the ratchet. The end of the angular portion 2^a of the body or sleeve and the end of the covering plate are reduced to receive a ring 12 which is freely rotatable around said reduced end and is 90 held in place by a collar 13 or in any other suitable manner. This ring has a thickened wall 12^a adapted to engage with either one of the lugs 11, and a spring 9^a acts to force the lugs apart and pawls in engagement 95 with the ratchet. The extremity of the angular extension 2^a is screw-threaded to engage with a handle 14 which is preferably hollow and provided with the cap 15. The hollow handle is adapted to inclose a variety of small tools which may be used in connection with the head 7. In order to hold the various tools in place within the head 7, I provide this head with a pivoted 100

latch 16, one end of which projects through the wall of the head 7, into the socket 8, the other end being provided with a button exterior to the head. A spring 18 holds the latch so that its end projects into the socket and into engagement with a recess in the tool carried by the head.

While any form of tool desired may be used with the handle heretofore described, I have shown in Fig. 1 a screw driver A which may be either formed so as to be received within the socket 8 of the head, or may be made solid with the socket, as desired.

In Fig. 3 I show a modified form of tool in which, in addition to the parts above described, a pressure shaft 20 is used. Preferably this is formed so as to be detachably engaged with the end of the shaft 5, as by the screw threads 21, the cap 3 being formed with an opening 13^a for this purpose. The extremity of this shaft 6 is provided with a knob 22 which is swiveled on the shaft 6 in any suitable manner.

The operation of my invention will be obvious from the description. The appropriate tool is inserted in the head 7 and held therein by the latch, whereupon the handle 14 may be turned to rotate the ratchet shaft 5, thus rotating the tool in the desired direction. By manipulating the ring 12, it will be seen that one or the other of the pawls may be raised from engagement with the ratchet, and thus a movement of the handle 14 in one or the other direction will act to rotate the ratchet in one or the other direction. It will also be obvious that by turning the ring so that both of the lugs 10 are allowed to move outward, both of the pawls will be in engagement with the ratchet and therefore hold the ratchet from any movement independent of the handle, and that thus the sleeve and the shaft 5 rotate together. Under ordinary circumstances, it is only necessary to operate the tool with the handle 14, but where considerable pressure has to be applied to the tool, or where working with the tool extending upward, then the pressure shaft with its knob is preferably attached to the end of the implement, as before described.

While I have shown what I believe to be the preferable form of my invention, I do not wish to be limited thereto, as it is obvious that many changes might be made without departing from the spirit of the invention.

Having thus described the invention, what I claim is:—

1. In an implement of the character described, a shaft having an enlarged socketed head at one end and a ratchet at the other, a tubular body having a recess at its

forward end to receive the inner end of the head and formed with a hollow angular extension circular in cross-section, the rear end of the body and rear face of the angular extension being open, a pawl pivotally mounted in the angular extension and engaging the ratchet, a cover-plate closing the rear end of the body and the rear face of the angular extension having its outer surface rounded to conform to the rounded contour of the angular extension and the body, said plate, the body and the angular extension entirely housing the shaft, the ratchet and the pawl.

2. In an implement of the character described, a shaft having an enlarged socketed head at one end and a ratchet in the other, a tubular body having a recess at its forward end to receive the inner end of the head and formed with a hollow angular extension, the said angular extension in cross-section forming a section of a circle, the rear end of the body and the rear face of the angular extension being open, opposed spring actuated pawls pivotally mounted in the angular extension and engaging the ratchet, a cover-plate closing the rear end of the body and extension and having a rounded outer face conforming in curvature to the curvature of the extension and the body and having an opening at its upper end in alinement with said shaft, said cover-plate, the body and the angular extension positively housing the shaft of the ratchet and said pawls, of a ring sunk into the face of the angular extension and having means for positively engaging one or the other of the pawls for shifting one or the other of the pawls out of engagement with the ratchet.

3. In an implement of the character described, a shaft having an enlarged socketed head at one end and a ratchet at the other, a tubular body having a recess at the forward end to receive the inner end of the head and formed with a hollow angular extension, the rear end of the tubular body and the angular extension being cut away, the cut-away portion intersecting the interior of the body and the angular extension, oppositely disposed pawls pivotally mounted within the angular extension and engaging said ratchet, each of said pawls having at its base a projecting portion extending out through openings in the angular extension, a handle forming a continuation of the angular extension, said handle being circular in cross-section and providing a seating shoulder, a cover-plate having an opening at one end, said cover-plate having a rounded face and being flat at one end to seat upon said seating shoulder, the exterior of the cover-plate conforming to the contour of the body and said angular ex-

tension, a pressure member adapted to pass through the opening in the plate and engage the shaft, and an interiorly recessed ring rotatably mounted upon the angular 5 extension and adapted to engage the said pawls to throw them into or out of engagement with the ratchet.

In testimony whereof I affix my signature in presence of two witnesses.
